CLAIM

The ornamental design for an elliptical pneumatic actuator for an electric switch, as shown and described.

DESCRIPTION

This application is related to a utility application entitled Elliptical Pneumatic Actuator With A Wedge Shaped Base naming the same inventive entity given herein.

FIG. 1 is a top, right side and front perspective view of an elliptical pneumatic actuator for an electric switch showing our new design;

FIG. 2 is a top, left side and front perspective view thereof;

FIG. 3 is a front view thereof;

FIG. 4 is a right side view thereof, the left side being a mirror image thereto;

FIG. 5 is a rear view thereof;

FIG. 6 is a bottom view thereof; and,

FIG. 7 is a top view thereof.

The broken line showing in the figure drawings is included for illustrative purposes only and forms no part of the claimed design.
